Primary Examiner — Richard Kearney

Assistant Examiner — Michael Hoffman

(57) **CLAIM**

The ornamental design for an oral waterjet, as shown and described.

DESCRIPTION

The patent or application file contains at least one drawing executed in color. Copies of this patent or patent application publication with color drawing(s) will be provided by the Office upon request and payment of the necessary fee.

3.1—front view of an oral waterjet showing my design;

3.2—back view thereof;

3.3—left view thereof;

3.4—right view thereof;

3.5—top view thereof;

3.6—bottom view thereof; and

3.7—perspective view thereof.

1 Claim, 7 Drawing Sheets
(7 of 7 Drawing Sheet(s) Filed in Color)
